ADJUSTABLE CLASP FOR NECKLACES OR THE LIKE

Michael Pagliuca, New York, N. Y., assignor to Alcore Novelty Company, New York, N. Y.

Application March 29, 1950, Serial No. 8,853

Term of patent 3½ years

(Cl. D45—4)

To all whom it may concern:

Be it known that I, Michael Pagliuca, a citizen of the United States, residing at 2309 Second Avenue, New York, in the county of New York and State of New York, have invented a new, original, and ornamental Design for an Adjustable Clasp for Necklaces or the like, of which the following is a specification, reference being had to the accompanying drawing, constituting a part hereof.

Fig. 1 is a perspective view of an adjustable clasp for Necklaces or the like showing my new design, illustrating the clasp in open position;

Fig. 2 is a top plan view of the clasp in an open position; and

Fig. 3 is a side elevational view thereof in a closed position.

I claim:

The ornamental design for an adjustable clasp for necklaces or the like, substantially as shown.

MICHAEL PAGLIUCA.
